UNITED STATES PATENT OFFICE.

JOHN A. BRILL, OF PHILADELPHIA, PENNSYLVANIA.

DESIGN FOR A RIB FOR CAR-SEAT PANELS.

SPECIFICATION forming part of Design No. 25,887, dated August 4, 1896.

Application filed June 20, 1896. Serial No. 596,346. Term of patent 14 years.

To all whom it may concern:

Be it known that I, JOHN A. BRILL, a citizen of the United States, residing at the city and county of Philadelphia, State of Pennsylvania, have invented and produced a new and original Design for a Detachable Rib for Car-Seat Panels, of which the following is a specification.

The essential feature of my design resides in the configuration of the rib, substantially shown in the accompanying drawings, in which—

Figure 1 is a front elevation; Fig. 2, a side elevation; Fig. 3, a plan view, enlarged; Fig. 4, a sectional view on the line $x-x$, Fig. 2; and Fig. 5, a like view on the line $y-y$, Fig. 2, both enlarged.

In front elevation, as in Fig. 1, the rib is rectangular in general outline, and in side elevation, as in Fig. 2, it takes the form of a reverse curve. The rib comprises side pieces 1, joined at the top by a plate 2, recessed, as at 3, and intermediate of their ends by cross-bars 4 and 5, the cross-bar 4 having a central enlargement 6 and rectangular holes 7, and the cross-bars 5 having holes 8.

As shown in Figs. 4 and 5, the cross-bars 4 and 5 join the side pieces 1 about flush with the rear thereof and form, with the inner surfaces of the arms 1, the exterior groove 9. 30

On each side of the side pieces 1 are formed grooves 10, parallel with the exterior configuration of the side pieces, as shown in Fig. 2.

At the rear of the top and bottom of the rib is formed gradually-increasing offsets 11 and 35 12. The offset 11 is provided with grooves 13, which merge into the rear of the rib, as will be noticed by comparing Figs. 4 and 5.

The formation of the grooves 10 in the sides of the arms 1 forms parallel flanges 14 and 15. 40

Having described my invention, I claim—

The design for a detachable rib for a car-seat panel, substantially as herein shown and described.

Signed at the city of Philadelphia, county 45 of Philadelphia, and State of Pennsylvania, this 15th day of June, 1896.

JOHN A. BRILL.
